Frederick Giles,
By J. M. Bowen, Atty.

UNITED STATES PATENT OFFICE.

FREDERICK GILES, OF SOUTH YARRA, VICTORIA.

SPRING-BUTTON.

SPECIFICATION forming part of Letters Patent No. 532,873, dated January 22, 1895.

Application filed May 14, 1894. Serial No. 511,186. (No model.)

To all whom it may concern:

Be it known that I, FREDERICK GILES, a subject of the Queen of Great Britain, and a resident of Fawkner Street, South Yarra, in the Colony of Victoria, have invented a certain new and useful Improvement in Spring-Buttons, of which the following is a specification.

This invention consists of an improvement in spring buttons for gloves, boots, shoes, leggins and the like whereby a constant spring is maintained, and also in means by which buttons of such class may be readily secured to the material required.

15 By spring buttons I refer to that class of fastenings wherein a metal cap is pressed over the head of a spherical or partly spherical button so as to form a hold on the flange of same and produce a securely fixed button to form portion of a clasp for holding together 20 the flaps of such gloves, boots, &c.

Reference may now be made to the accompanying drawings, in which—

Figure 1 shows an improved spring button 25 one half in elevation and one half in vertical section in the head or sphere of which a spiral spring is set. Fig. 2 shows a plan of an ordinary spherical button. Fig. 3 shows a plan of an annular plate provided with prongs 30 which is passed over the spherical head of the button. Fig. 4 shows my improved button with its annular ring in position for securing on a glove or boot the material forming such glove or boot being indicated by M. Fig. 5 shows a vertical cross-section of one of my 35 spring buttons with a securing ring resting on top of its base and provided with staples which may be employed for securing the button to the fabric. Fig. 6 shows an independent clip 40 staple for securing a perforated base of a spring button to fabric.

In the drawings "A" (Fig. 2) shows an annular plate or ring of metal which is provided with two or more spikes "A'" preferably of 45 about a quarter of an inch in length and pointed at their ends. These spikes are preferably formed in one piece with the annular plate and are turned over at right angles to same. (See Fig. 4.) This metal ring is passed 50 over the head of a button and stopped against the flange of same (see Fig. 5) so as to place it around its shank and its spikes or pins "A'"

are pressed through the leather or other material in the position desired for fastening and may be clinched over on the other side of the 55 leather or flap by the employment of specially constructed pinchers hereinafter to be referred to.

If preferred the spring button may be constructed with a perforated square or circular 60 plate secured to and above the flange "B" (Fig. 4) so as to allow the projecting spikes "A'" of the annular plate "A" to pass through the perforations on such plate; or the plate of the spherical button may be otherwise se- 65 cured to the annular ring "A."

Aspiral spring "C" is inserted in the spherical head of the button (which I prefer to employ, see Fig. 1) and indents "D" are formed in the exterior of the hemispheres which keep 70 the said spring in position. Such spiral spring is shown to have its middle coils of larger diameter than its end coils, and thereby the elasticity of the spring is increased and it is made possible to bring such middle coils to also rest 75 directly upon the hemispheres forming the head of the button.

The central apertures of rings A and B are made sufficiently large to permit the same to be passed over the button head when attaching the buttons to or detaching the same from the material, and it will be seen that owing to this arrangement, if one of the fastening spikes should become accidentally destroyed, the same button head may again be employed, 85 a new part only being substituted for the part carrying such spikes.

The manner of securing the button on to the flap of a boot or glove is as follows: The spring button is brought into the desired position on 90 the flap and the annular ring "A" passed over its head so as to grasp its flange or plate and the spikes "A'" of said annular ring are passed through the material to which it is desired to secure the button. Then, suitably formed 95 pinchers are employed whereby the spikes or pins on the annular ring A are forced inwardly so as to approximately meet about a common center, thereby forming a neat and secure hold of the material to which the button is 100 fastened.

When applying my invention to boots the buttons would probably be sewed on to the boots by thread through the perforated flange

or plate "B" and would be easily removed by cutting the thread and may then be secured in the position to fit the purchaser by means of the annular ring with its spikes passing over the flange and clinched as described.

Referring to Fig. 6 it will be seen that the clip staple there illustrated is an appliance for securing the perforated flange or spring buttons to the material by passing the points of the staple through the perforations and then turning same over by pinchers as hereinbefore described. However, I desire to have it understood that my spring buttons may be provided with any suitable bases and may be attached to fabric in whatever way that may be most convenient in each case.

Having now particularly described and ascertained the nature of my said invention and in what manner the same is to be performed, I declare that what I claim is—

1. A spring button having its head made of two sections separated vertically but united

at the shank, combined with a spring inserted between said sections and extending across the space separating the same, substantially 25 as set forth.

2. A spring button made in semispherical hollow sections united at the shank, combined with a spiral spring inserted between such sections, substantially as set forth. 30

3. A spring button made in semispherical hollow sections united at the shank, combined with a spiral spring inserted between said sections, and indentations in said sections for confining the ends of the spring in position, 35 substantially as set forth.

Signed this 16th day of March, 1894.

FREDERICK GILES.
